Primary Examiner — Susan Bennett Hattan*Assistant Examiner* — Leanne Was-Englehart(74) *Attorney, Agent, or Firm* — Young & Thompson(57) **CLAIM**

The ornamental design for a thermostat, as shown and described.

DESCRIPTION

FIG. 1 is a front elevation view of a thermostat showing the new design;

FIG. 2 is a front, top, and right side perspective view thereof, wherein the opposite side perspective view is a mirror image;

FIG. 3 is a left side elevation view thereof; and,

FIG. 4 is a top plan view thereof; wherein the bottom plan view appears the same.

The broken lines shown in the drawings illustrate portions of the thermostat that from no part of the claimed design.

1 Claim, 4 Drawing Sheets(56)
